P. P. O'BRIEN.
Thill-Coupling.

No. 224,218.

Patented Feb. 3, 1880.

Inventor:-
Patrick P. O'Brien.
By O. Drake, Atty.

UNITED STATES PATENT OFFICE.

PATRICK P. O'BRIEN, OF SUMMIT, NEW JERSEY.

THILL-COUPING.

SPECIFICATION forming part of Letters Patent No. 224,218, dated February 3, 1880.

Application filed December 20, 1879.

To all whom it may concern:

Be it known that I, PATRICK P. O'BRIEN, of Summit, in the county of Union and State of New Jersey, have invented certain new and useful Improvements in Thill-Couplings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to produce a thill-coupling that can be readily connected to the axle of a carriage or other vehicle without the usual means of a bolt and nut, and thereby to do away with the necessity of using a wrench or other inconvenient means of connecting said coupling.

The object is also to prevent said coupling from rattling when in action without using the destructive, and therefore expensive, means of elastic packing, and to produce a coupling that will be durable and generally convenient.

The invention consists in the combination of a thill-iron with pivotal projections cast or otherwise formed upon its inner or coupling extremity with socketed jaws for the reception of said thill-iron, a clamping device for the purpose of securing said thill-iron in said socketed jaws, and also to hold the shafts or thills in any desired position when not in use.

Referring to the accompanying drawings, in which similar letters of reference indicate like parts, Figure 1 is a side elevation, showing the parts in position ready for operation. Fig. 2 is a section of the same, taken through line *x*. Fig. 3 is a bottom-plan view; and Fig. 4 is a side view, showing the clamp with its lever attachments open and the thill-iron removed.

In carrying out my invention I cast or otherwise construct upon the inner or coupling extremity of the thill-iron A the pivotal pro-

jections *a*, which work in and conform to the bearings *b*, Fig. 4, within the socketed jaws *c*. Upon the outer sides of the said socketed jaws *c*, I pivot, as at *d*, the lever *e*, which, when the coupling is in position for drawing, as in Figs. 1 and 3, passes around the plate *f*, and is held in position by the pivoted safety catch or button *g*.

The lever *e* is attached in the manner indicated, Figs. 1 and 4, to the connecting-rod *h*, which forms, in connection with the clamp *i*, a clamping device to hold the thill-iron in position.

The connecting-rod *h* is fastened to the clamp-iron *i* by means of a screw, *j*, which screw serves to regulate the tension upon the cylinder *k* of the thill-iron, and prevents all possibility of said cylinder rattling within the jaws *c*.

The action of operating the invention is extremely simple.

To disengage the coupling I first turn the pivoted catch or button *g* to free the lever *e*, then turn the lever *e* down, which action throws the connecting-rod *h*, with its attending clamp-iron *i*, upward and backward off from upon the pivotal projections *a*, as shown in Fig. 4, and thus allows the thill-iron A to be taken from the socket.

It is evident that the lever *e*, when in the position shown in Fig. 1, the pivotal point *d* being past the center *d*, will stay in the position indicated in said Fig. 1 without the aid of the pivoted safety catch or button *g*; but I have adopted the latter out of abundant caution to prevent accidental displacement.

The pivot upon which the safety-catch *g* revolves should be shouldered at *g'*, to prevent the nut *m* from bearing too hard upon said catch *g*.

Having thus described my invention, what I claim, and wish to have secured by Letters Patent, is—

1. The combination, with the thill-iron and the jaws, arranged as shown, of the lever *e*, pivoted to said jaws, the clamp-iron *i*, and the connecting-rod *h*, pivoted to the short arm

of said lever *e*, and secured to said clamp-iron, and operating substantially as and for the purposes set forth.

2. The combination, with the lever *e*, of the 5 safety catch or button *g*, as and for the purpose set forth.

3. The combination, with the thill-iron and the socketed jaws, arranged as shown, of the lever *e*, clamp-iron *i*, connecting-rod *h*,

and the screw *j*, arranged and operating substantially as and for the purpose set forth.

In testimony that I claim the foregoing I have hereunto set my hand this 3d day of December, 1879.

PATRICK P. O'BRIEN.
